UNITED STATES PATENT OFFICE

169,807

COMBINATION AUTOMOBILE-AIRPLANE

Adelard J. Gero, Jr., Taftville, Conn.

Application August 26, 1952, Serial No. 21,197

Term of patent 14 years

(Cl. D71—1)

To all whom it may concern:

Be it known that I, Adelard J. Gero, Jr., a citizen of the United States, residing at Taftville, in the county of New London, State of Connecticut, have invented a new, original, and ornamental Design for a Combination Automobile-Airplane, of which the following is a specification, reference being had to the accompanying drawings forming a part hereof.

In the accompanying drawings:

Figure 1 is a perspective view of a combination automobile-airplane showing my new design with the left wing panel extended in flight position while the right wing panel is folded aft spanwise and vertically chordwise.

Fig. 2 is a top plan view of my combination automobile-airplane with the wings in extended flight position.

Fig. 3 is a front elevation view of my combination automobile-airplane with the wings in extended flight position.

Fig. 4 is a side elevation view of my combination automobile-airplane with the wings in extended flight position.

Fig. 5 is a top plan view of my combination automobile-airplane in condition for use as an automobile and with the wings folded aft.

Fig. 6 is a side elevation view of my combina-

tion automobile-airplane in condition for use as an automobile and with the wings folded aft.

Fig. 7 is a rear elevation view of my combination automobile-airplane in condition for use as an automobile and with the wings folded aft; and

Fig. 8 is a front elevation view of my combination automobile-airplane in condition for use as an automobile and with the wings folded aft.

I claim:

The ornamental design for a combination automobile-airplane, substantially as shown.

ADELARD J. GERO, JR.
